UNITED STATES PATENT OFFICE.

JOHN SELLERS BANCROFT AND MAURITZ C. INDAHL, OF PHILADELPHIA, PENNSYLVANIA, ASSIGNEES TO LANSTON MONOTYPE MACHINE COMPANY, OF PHILADELPHIA, PENNSYLVANIA, A CORPORATION OF VIRGINIA.

RECORD-STRIP COMPOSING-MACHINE.

1,149,175.

Specification of Letters Patent. Patented Aug. 10, 1915.

Application filed July 27, 1914. Serial No. 853,388.

To all whom it may concern:

Be it known that we, JOHN SELLERS BANCROFT and MAURITZ C. INDAHL, citizens of the United States, residing at Philadelphia, in the county of Philadelphia and State of Pennsylvania, have invented certain new and useful Improvements in Record-Strip Composing-Machines; and we do hereby declare the following to be a full, clear, and exact description thereof, reference being had to the accompanying drawings, forming part of this specification, and to the figures and letters of reference marked thereon.

This invention relates to improvements in typographic composing machines wherein each unit of the composed matter is represented by a selective or designating member, such as a finger key, and it has for its principal object to provide means whereby the mechanism responding to a selective or designating member when once set in motion is continued in action and caused to automatically repeat its functions until arrested.

A machine embodying a repeat action of this kind is illustrated in Patent No. 938,298, dated Oct. 26, 1909, wherein a special or repeat key is coupled with the starting mechanism of the punch and feed motor in a manner to cause the starting mechanism to be automatically actuated by and during the return stroke of said motor, thereby converting the otherwise single-acting motor into one capable of continuous operation so long as the conditions produced by the depression of the repeat key are maintained.

The present invention is primarily designed to provide a repeat mechanism which may be employed in connection with the standard equipment or in connection with the mechanism of Patent No. 944,405, dated December 28, 1909, without extensive change or alteration and which will be effective for giving repeat designations of any character or characters on the key board by the simple manipulation of the key indicating the desired character or characters in connection with a repeat key which throws the repeat mechanism into action.

While the invention is primarily designed for embodiment in such a standard equipment, nevertheless it embodies features which are in themselves novel and competent for use in connection with any selec-

tive designating key board mechanism and might well be incorporated in key board designating mechanism, especially designed for use in combination therewith, and hence it is not desired to limit the invention to a particular type or style of equipment.

Referring to the accompanying drawings,—Figure 1 is a sectional elevation of a portion of a record strip composing machine, many of the well known parts being omitted, but which will be readily understood from the parts indicated in the drawings in connection with the mechanism shown in Patent No. 944,405, before referred to. Fig. 2 is a detail sectional elevation looking at the rear of the repeat motor mechanism shown in Fig. 1. Fig. 3 is a detail showing the repeat lock operating bar and the lock or latch. Fig. 4 is a detail perspective of one of the two-part valve controller bars. Fig. 5 is a perspective view showing one arrangement for supplying air pressure to the repeat motor.

Like reference numbers in the several figures indicate the same parts.

The parts of the machine illustrated in the drawings in connection with the parts constituting the present invention and which correspond to similar parts in the mechanism of Patent 944,405, briefly stated, are the rocker frames formed by the rock shafts 174 with their bails 175 adapted to form the connections between the key bars and the valve controlling bars; the valve controlling bars provided with projections 176 with which the bails 175 on the rocker frames co-operate; and the key bars which co-operate with the upper bars of said bails having the usual downwardly extending projections thereon. The arrangement of projections on the bars corresponds to the well known arrangement for effecting the selective operation of the valves controlling the punches. The valve stems are indicated at 170, and it will be understood that when said valve stems are moved longitudinally by the longitudinal movement of the valve operating bars 173, pressure will be admitted to the corresponding cylinders of the pneumatic motor mechanism for advancing the punches and making the proper selective designations or indications in the paper strip.

The paper feeding mechanism corresponds

to that of the before-mentioned patent and at 146 there is indicated the valve for controlling the admission of pressure beneath one or the other of pistons 137 and 138, which pistons are connected with a rocking frame 139.

The foregoing reference numbers all correspond to reference numbers on corresponding parts of the mechanism in said patent, from which the detail construction and operation will be readily understood.

In the operation of such mechanism when a proper valve operating bar is moved longitudinally to operate its valve stem, the corresponding punch will be advanced, whereupon the valve 146 will be moved to admit pressure beneath the piston 138 to retract the parts preparatory for a new feed and rewind the motor spring of the paper take-up portion of the paper feeding mechanism, and upon the retraction of the punch the valve 146 will be moved back to its normal position and admit air underneath piston 137 so as to advance the paper one step and this sequence of operation is repeated every time a key in the key board is depressed and again released.

The mechanism for carrying into effect the repeat action of the present invention makes provision whereby when a selective designating key or device such as one or the other of the keys 180 is operated in conjunction with a repeat key or device, the key 15, for example, and the keys held depressed, the valve stem and valve normally operated by the selective designating key will be operated a plurality of times, thus effecting the repeated operation of the designated punch or punches. To carry this into effect in a simple manner, the valve operating bars are preferably made in two sections 173 and 173^a arranged side-by-side, one of said sections being provided with the projections 176 before referred to, and the other of said sections being advanced in unison therewith through the medium of a spring 10, connected with a lug or projection 11 on the section 173, and a coöperating lug or projection 12 on the section 173^a. The section 173^a is adapted for direct engagement with the valve stem and the section 173 for engagement by the operating bail. Under the tension of the spring 10, the sections of the bar are held in their proper relative position with sufficient rigidity to actuate the valve, and their relative position is determined by the engagement of lugs 13 and 14 projecting downwardly from the sections and offset to intersect as shown in Fig. 4. With this arrangement, even though the designating key be held depressed, the valve stem engaging section of the bar may be moved reversely against the tension of the spring 10, and a motor mechanism is provided for so moving the section periodically in time with the

paper feed movements, and under the control of a repeat key indicated in Fig. 1 at 15. This repeat key 15 may correspond in construction to the designating key 180 of the key board, and is adapted to coöperate with 70 and advance a repeat key bar 16 corresponding in form and arrangement to the designating key bars but having no downwardly extending projections for coöperation with the bails of the rocker frames. 75

At its inner end the repeat key bar is adapted to coöperate with and actuate a repeat key lever 17 journaled in bearings at its lower edge, as shown in Fig. 2, and having an arm 17^a resting behind a projection 18^a 80 on a bar 18 mounted to slide in the key board frame in manner similar to the valve operating bars before referred to. The end of the bar 18 is adapted to coöperate with mechanism for controlling the repeat motor, 85 that is to say, when advanced by the operation of the repeat key it releases the repeat motor and the latter immediately begins to operate in such wise as to effect an intermittent operation of the valves which have 90 been designated by the selecting devices of valve actuating bars.

The repeat motor and parts immediately associated therewith are all preferably secured to the valve casing and can be removed with it; thus, the key board as a whole is formed in units, as it were, which may be separately adjusted and then assembled together in the casing to form a complete machine. The motor mechanism referred to embodies a pair of oppositely disposed cylinders 19 provided with pistons 20. As will be presently described, pressure is supplied to the cylinders 19 alternately in time with the pressure supplied to operate 100 the pistons 137 and 138 and the pistons 20 will when permitted to operate be reciprocated in time with the punches and paper feed. Between the proximate faces of the pistons there is mounted the end of an arm 11 21 projecting from a rocking frame 22 journaled in bearings supported from the valve casing and having a transverse member or bar 23 normally occupying a position in front of the downward extensions 173^b of 11 the valve operating bars 173. The normal position of the rocking frame and transverse bar 23 is such that the movement of the valve operating bars is not interfered with and when no repeat action is desired 12 the said bars operate in all respects as in the commercial machine and patent hereinbefore referred to, but when the repeat action is desired the repeat motor is set into operation in time with the paper feed and the rocking frame is thereby oscillated, whereby the transverse bar 23 periodically pushes the yielding forward sections of the valve operating bars reversely or against the tension of the springs 10, the number of 1:

such movements depending upon the time the keys are held depressed and the repeat motor is allowed to continue in action.

For normally restraining the operation of the repeat motor and holding the parts in a definite position when brought to rest, a lock or catch is provided which is adapted to be released by the repeat bar 18 when advanced by the operation of the repeat key.

10 The simple and preferred arrangement adopted embodies an angle lever 24 journaled at an intermediate point on the repeat motor frame and having one arm extending at 25 into position immediately in front of 15 the end of the repeat bar 18 while the other arm is provided with a shoulder 26 to co-operate with an adjustable stop formed by a set screw 27 mounted in an arm 28 on the oscillatory frame 22. The relation of 20 the parts is such that when the catch or shoulder 26 is in engagement with the stop 27 the oscillatory frame 22 will be held in the position shown in Fig. 1, that is to say, in its inoperative position and with the 25 piston 20 of the lower cylinder 19 retracted. The latch formed by the angle lever 24 is held in the position last referred to by a spring 29 and is released from its engagement with the oscillatory frame to permit 30 the repeat motor to operate, by the movement of the repeat bar 19 when advanced by the repeat key 15.

The arrangement described normally holds the oscillatory frame in a definite position at all times when the repeat key is not depressed, thus insuring accurate counting of the registering mechanism of the keyboard and preventing any possible interference with the parts of the mechanism when 40 no repeat action is desired.

The repeat motor will operate to oscillate the frame 22 just so long as the repeat key is held depressed, and if at the same time any of the designating keys are also depressed the punches selected thereby will be operated a corresponding number of times to make repeat designations in the record strip.

45 The pistons 20 of the repeat motor are preferably of cylindrical formation, open at the inner ends to receive projections 35 on screw plugs 36 forming the rear cylinder heads. Said projections do not fit the chambers in the pistons tightly, but they form 55 stops for limiting the rearward movement of the pistons and are susceptible of adjustment with the plugs 36 and may be fastened in adjusted position by lock nuts 37 on the plugs.

60 The proper timing of the movements of the repeat motor may be best secured by a control of the air pressure through the operation of the punches. In the commercial machine as well as in the machine of patent, 65 a valve 146 of the D-type is operated by a

rock shaft having a bail overlying shoulders on the punch bars, to admit pressure alternately to the cylinders 137 and 138 and this valve may be utilized to similarly control the admission of pressure to the cylinders 70 of the repeat motor. An arrangement of this kind is shown in Fig. 1, where ducts or pipes 52 lead from the valve to the cylinders of the repeat motor. A convenient arrangement is to extend the ducts 52 from 75 the bottoms of the cylinders 137 and 138, although it is obvious that they may be branched at any desired point from the ducts leading from the valve.

It is not important that the same valve 80 be employed for admitting pressure to both the repeat motor and cylinders 137 and 138, and in Fig. 5 an arrangement is shown in which an independent valve is employed.

In the arrangement last referred to the 85 usual rock shaft and bail are shown at 40 and on the opposite side of the punch bars 41 there is a second rock shaft 42 having a bail 43 in position for co-operation with the shoulders on the punch bars which engage the bail 40. The bail 43 is lifted by the punch bars and returned by elastic pressure preferably supplied by constant air pressure in a cylinder 44 in which works a piston connected by rod 45 with a rearwardly extending arm 46 on the rock shaft. The rock shaft carries an arm 47 having a cam slot 48 therein for the reception of a stud on one arm 49 of an angle lever pivoted on the frame. The other arm 50 of the 100 angle lever engages and operates a valve 51 for controlling the admission of pressure through the ducts 52 to the cylinders of the repeat motor. The valve 51 is similar to the valve 146 before referred to but is operated by the rock shaft and bail 42 and 43 while the valve 146 is operated by the rock shaft and bail 40. With this arrangement the operation of the repeat motor may be timed in any preferred relation to the punch 110 movements to secure the most desirable or highly efficient action.

115 In operation the designating key and repeat key are both depressed or operated and the normal action of the designating key on its selector motor is repeated by the action of the repeat motor.

From the foregoing description it will be seen that the valve operating bars form in effect a plurality of key controlled selecting 120 devices, and the repeat motor while described as one dependent for its operation upon a pressure power medium, obviously may be of any other known type, with control connections designed for effecting the 125 actuation of the same in time with the operation of the designating punches, whereby the desired punches will be advanced primarily through the operation of their normal designating keys and the repeating op- 130

eration continued when the repeat key is operated in conjunction with the normal designating key.

Having thus described our invention, 5 what we claim as new and desire to secure by Letters Patent of the United States, is:

1. In a record strip composing machine, 10 the combination with a plurality of designating keys, a plurality of selectors operated by said keys and a plurality of punch motors, one controlled by each selector, of a repeat mechanism embodying an intermittently acting repeat motor, operating connections intermediate said motor and 15 selectors for retracting the latter against the pressure of their designating keys, and a repeat key controlling the operation of said repeat motor.

2. In a record strip composing machine, 20 the combination with a plurality of designating keys, a plurality of selectors controlled thereby, and a plurality of punch motors, one for each selector, of spring supported members intermediate the designating 25 keys and punch motors, and a repeat mechanism embodying an intermittently operating repeat motor, and operating connections intermediate said repeat motor and 30 selectors for retracting the spring supported members whereby the punch motors will be operated a plurality of times during the depression of the designating keys.

3. In a record strip composing machine, 35 the combination with a plurality of designating keys, a plurality of spring supported selectors controlled by said keys, and a plurality of punch motors, one for each selector, of a repeat motor, connections intermediate said motors and selectors for retracting 40 the selectors operated by the designating keys, against the tension of their supporting springs, and a repeat key controlling the operation of the repeat motor.

4. In a record strip composing machine, 45 the combination with a plurality of designating keys, a plurality of selectors operated by said keys and a plurality of punch motors one for each of said selectors and adapted to be controlled by the movement of the 50 designating keys, of a repeat mechanism embodying an intermittently operating repeat motor, a selector retracting device operated by said repeat motor, for periodically returning the actuated selectors to normal 55 position against the pressure of their designating keys, whereby the punch actuating motors will be operated intermittently during each designation, and a repeat key controlling the operation of the repeat motor, 60 whereby punch motors controlled by the designating keys may be caused to operate intermittently by the simultaneous depression of the designating keys and repeat key.

5. In a record strip composing machine, 65 the combination with key controlled select-

ing devices, each embodying a spring supported portion and punch actuating motor, mechanism controlled by said spring supported portion of the selecting devices, of an intermittently operating repeat motor 70 mechanism embodying a selector engaging member for periodically retracting the spring supported portions of the actuated selectors, whereby the punch motor mechanism controlled thereby will be intermittently operated.

6. In a record strip composing machine, 75 the combination with key controlled selecting devices, each embodying a spring supported extension, and punch actuating motor mechanism controlled by the spring supported extensions of said selecting devices, of an intermittently operating repeat motor mechanism coöperating with said selector extensions whereby the punch motor mechanism controlled thereby will be intermittently operated.

7. In a record strip composing machine, 80 the combination with key controlled selecting devices each embodying a spring supported extension and punch motor mechanism controlled by said selector extension, of an intermittently operating repeat motor, a bar operated thereby and coöperating 85 with the selector extensions to retract the same periodically when advanced by their designating keys, and a repeat key controlling the operation of said repeat motor.

8. In a record strip composing machine, 90 the combination with key controlled selecting devices each embodying a yielding extension, a plurality of punch actuator motor control devices, one for each selector extension, and an intermittently operating record strip feed motor, of a repeat motor operating in time with the operation of the punches, means operated by said repeat motor for retracting the yielding extensions of the actuated selectors periodically, and a repeat key controlling the repeat motor 100 whereby the repeat motor may be thrown into operation at will.

9. In a record strip composing machine, 105 the combination with a series of parallel key controlled selecting devices each embodying a spring supported extension, and punch motor controlling devices actuated by said extensions, of a repeat mechanism embodying a reciprocatory motor mechanism, a member moved by said repeat motor mechanism and coöperating with the extensions of all actuated selector devices for periodically retracting the same, whereby the punch motors will be operated intermittently, and a repeat key controlling the operation of said repeat motor mechanism.

10. In a record strip composing machine, 115 the combination with designating keys, a plurality of parallel longitudinally movable selector bars, actuated by the keys, and 120

each embodying a main section and a spring supported supplemental section, and punch actuating motor controlling devices with which said supplemental sections of the selector bars coöperate, of a reciprocatory repeat motor mechanism coöperating with the supplemental sections of the actuated selector bars for periodically retracting the same to effect the intermittent operation of the 10 punch motors, and a repeat key controlling the operation of the repeat motor mechanism.

11. In a record strip composing machine, the combination with the designating keys, 15 punch motor valves and longitudinally movable valve operating bars, and means whereby the operative ends of said bars are advanced with a yielding pressure to actuate the valves, of an oscillatory repeat motor mechanism coöperating with the yielding ends of the actuated valve operating bars, and a repeat key for controlling the repeat motor mechanism.

12. In a record strip composing machine, 25 the combination with designating keys, punch motor valves, and valve operating bars controlled by the keys, each embodying a yielding valve engaging section, of a repeat mechanism embodying a repeat motor 30 and a transverse bar operated thereby and coöperating with the yielding sections of the actuated valve operating bars to positively retract the same and permit the valves to close, and a repeat key controlling the operation 35 of the repeat motor.

13. In a record strip composing machine, the combination with longitudinally movable key controlled punch motor valve operating bars formed in sections yieldingly con-

nected together, connections intermediate 40 one section of each bar and a designating key, and valve stems with which the other sections coöperate, of a transverse reciprocatory bar coöperating with the valve engaging sections of the said valve operating 45 bars to move the same into retracted position, a reciprocatory repeat motor connected with said reciprocatory bar for operating the same, a catch controlling the repeat motor, and a repeat key controlling said catch. 50

14. In a record strip composing machine, the combination with longitudinally movable bars formed in sections yieldingly connected, designating keys with connections intermediate said keys and one of the sections of said bars, punch motor controlling valves with which the other of the sections of said bars coöperate, and a record strip feeding motor embodying a pressure operated piston, of a repeat mechanism embodying a pressure operated piston, a reciprocatory member actuated thereby, and coöperating with the punch valve engaging sections of the bars to move the same into retracted position, a pressure duct common to 65 the repeat motor and paper feed motor, a catch for arresting the movement of the repeat motor, and a repeat key controlling said catch, whereby upon the operation of said repeat key the repeat motor will be actuated in time with the record strip feed motor, to periodically release the actuated punch motor valves. 70
